UNITED STATES PATENT OFFICE.

MOSES MOSLER, OF CINCINNATI, AND CARL BARTELS, OF HAMILTON, OHIO, ASSIGNEES
TO THE MOSLER SAFE COMPANY, OF NEW YORK, N. Y.

SAFE CONSTRUCTION.

1,087,175.

Specification of Letters Patent. Patented Feb. 17, 1914.

Application filed April 23, 1913. Serial No. 763,023.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe Construction, of which the following is a specification.

16 This invention, pertaining to safe-construction and relating particularly to the construction of the doors of round-door safes, will be readily understood from the following description taken in connection 15 with the accompanying drawing in which:—

Figure 1 is a rear elevation of a round safe door embodying an exemplification of our invention, part of the rear door-member being broken away to expose parts to the 20 rear of it; Fig. 2 a diametrical section of the same in the plane of line *a* of Fig. 1; and Fig. 3 a section at right angles to the plane of the general structure and in the plane of line *b* of Figs. 1 and 2.

25 In the drawing 1, indicates the front door-member of a round door safe; 2, the stepped margin thereof; 3, an annular flange on the rear of the front door-member, the exterior of this flange entering also into the formation 30 of the marginal steps of the door, the front door-member with its flange being integrally formed and preferably formed of manganese steel or other non-cuttable metal, our present invention peculiarly lending 35 itself to the construction of safe doors of such material; 4, the circular recess formed in the rear of the door by reason of the presence of the marginal flange; 5, a rabbet formed in the rear of the interior of flange 40; 6, a rear door-member consisting of a circular plate of machinable metal whose periphery fits within the rabbet of the flange; 7, lugs projecting inwardly from the flange in front of plate 6, the front surfaces of these 45 lugs being beveled or helically formed, as indicated in Fig. 3, so as to form something of the nature of an interrupted screw; 8, hooks projecting from the front face of plate 6 and engaging in front of lugs 7; 9, a 50 circular series of hooks projecting from the rear face of the front door-member and disposed, preferably, about midway between the periphery and the center of plate 6, the forwardly presenting faces of these hooks 55 having helical surfaces like those of lugs 7;

10, hooks, like hooks 8, projecting forwardly from plate 6 and adapted to engage hooks 9; 11, rings projecting rearwardly from plate 6 and adapted to serve as the circular bolt-frame after the manner usual in round-door 60 safes; and 12, a pin passing through plate 6 and to a position in front of one of the hook-engaging members on the front door-member.

The parts are to be so constructed, in an 65 obvious manner, that when plate 6, forming the rear door-member, is placed in position in the rabbet of the flange of the front door-member and then given a partial turn the helical character of the hooking-engage- 70 ments will cause the two door-members to be drawn firmly together. Then, pin 12, having been fitted tightly to place, prevents the unscrewing of the parts, so to speak, and maintains the two door-members in firm and 75 fixed relationship, pin 12 illustrating merely a typical device for effecting this main-tenance.

Machinable plate 6 while truly a door-member, does not coöperate with the door-jamb, which door-jamb is closed entirely by front door-member 1, the plate thus not being strictly an element of safe closure. The engagement of the periphery of the plate with the rabbet of the front door-member 80 serves in centering the plate, thus bringing the circular door-frame concentric with the front door-member. The plate, having been properly fitted to the front door-member, 85 may be removed and dealt with independ- 90 ently of the front door-member, which latter will generally be of massive construction. The plate, or bolt-frame as it really is, having been removed, may be machined and fitted up with its bolts, locks and other ac- 95 cessories, and tested out complete as to the movements of its parts without the neces- 100 sity of the presence of the front door-member. The front door-member, having been fitted to the door opening of the safe, in the absence of the bolt-frame the bolt-frame may then be applied in position and firmly secured to the front door-member, thus completing the 105 door and its accessories upon its inner face. If, at any later time, it becomes necessary or desirable to materially modify the rear ac- 110 cessories of the door, plate 6, with the parts borne by it, may be removed from the front door-member without the necessity for un-

shipping the heavy door-member and without detracting in any degree from the completeness of the door as an element in closing the door-jamb. When the rear plate is 5 replaced upon the front door-member, or when a substitute rear plate is placed upon the front door-member, there need be no refitting of the rear plate with reference to the door-jamb, for the reason that the rear 10 plate has no contact with the door-jamb.

The improved construction has been referred to as safe-construction but it is to be distinctly understood that such construction is applicable to safes of such small size and 15 portable character as are generally referred to as safes, and also to larger fixed safe-constructions usually referred to as vaults. In other words, by the expression "safe-construction," as used in the present specification and claim, we mean safe and vault 20 construction.

We claim:—

Safe construction comprising, a circular front door-member, a circular plate disposed 25 at the rear of the front door-member and provided with rearwardly projecting rings forming a circular bolt-frame and having its periphery of a size adapted to be at all times

free of contact with the door-jamb, means for centering said plate relative to the front 30 door-member, a circular series of hooking lugs on the rear portion of the front door-member near its periphery, hooking lugs projecting from the front of said plate and adapted to be engaged with the lugs of the 35 front door-member by an angular motion of the plate relative to the front door-member, a second circular series of hooking lugs on the rear portion of the front door-member concentric with the first series but disposed 40 radially inward between said first series and the axis of the door-member, a second series of hooking lugs on the front of said plate to coöperate with the second series of hooking-lugs on the front door-member and engaging the same by an angular motion of the plate relative to the front door-member, and a locking device to prevent displacing angular motion of said lugs, combined substantially as set forth.

MCSES MOSLER.
CARL BARTELS.
